UNITED STATES PATENT OFFICE.

ALEXANDER PEACOCK AND THOMAS HERBERT HUTCHINSON, OF BIRMINGHAM,
ENGLAND.

CONTROLLING MECHANISM FOR POWER-PRESSES AND OTHER PURPOSES.

1,322,134.

Specification of Letters Patent.

Patented Nov. 18, 1919.

Application filed October 16, 1917. Serial No. 196,892.

To all whom it may concern:

Be it known that we, ALEXANDER PEACOCK and THOMAS HERBERT HUTCHINSON, subjects of the King of Great Britain, and residents of Wyrley Road, Witton, Birmingham, in the county of Warwick, England, and 64 Doidge road, Gravelly Hill, Birmingham aforesaid, respectively, have invented new and useful Improvements in 10 Controlling Mechanism for Power-Pres-
ses and other Purposes; and we do hereby declare the following to be a full, clear, and exact description of the same.

Our invention comprises improvements in 15 controlling mechanism for power presses and other purposes.

In our prior British specification No. 22104 A. D. 1914 we have described a form of safety device or guard for power presses 20 and other purposes which is so connected to the operative part of the press that the guard cannot be raised except when the press is stopped and held in its stopped condition; all being so arranged that the press 25 stops after each cycle of operations on the part of the ram. In practice, owing to the fact that the press may be required to pierce a number of articles from a single strip or piece of metal, it is undesirable and waste 30 of time for the press to stop after each operation and the main object of the present invention is to provide means whereby the press may be set to function for a variable number of times according to the size of the 35 strip to be fed into the machine and to the number of pressings which it is required to produce from the one piece of metal.

More particularly the invention relates to that class of controlling device which includes a counting mechanism whereby the machine is stopped after it has functioned a predetermined number of times.

The invention is also applicable to a variety of other purposes where it is required to stop the movement of mechanism at the end of a predetermined but variable number of movements.

As applied to a power press the lever may carry a guard and be connected to a plunger 50 or bolt adapted to engage with the ram of the press; all in manner described in our prior British specification No. 22104 A. D. 1914.

Referring to the drawings:—

55 Figure 1. is a side elevation of a press

fitted with controlling mechanism according to this invention.

Fig. 2. illustrates the right hand side of the lever and controlling mechanism with the plunger engaged. 60

Fig. 3. is a similar view with the plunger disengaged.

Fig. 4. illustrates the opposite or inner side of the lever with the plunger engaged.

Fig. 5. is a similar view with the plunger 65 disengaged.

Fig. 6. is a plan of same.

Figs. 7, 8, 9 and 10, are respectively vertical cross sections at 7—7, 8—8, 9—9, and 10—10, in Fig. 5, looking in the direction 70 from left to right.

In carrying our invention into practice as illustrated upon the accompanying drawings the lever 1 is so arranged that when it is raised above the horizontal the guard is 75 lifted this guard 2 being shown as carried by the said lever and the press locked in an inoperative position, while when the lever is lowered to a horizontal position the press is started, when it functions for one or more 80 predetermined number of times according to the setting of the selective mechanism, or under the influence of a personal control of the operator the press may function for an unlimited number of times without stopping. 85

The driving clutch may be conveniently normally engaged by a spring and the lever 1 carries mechanism whereby each time the lever is lowered the clutch is engaged and held in engagement until the press has functioned the predetermined number of times, a rod 3 being provided connected to the lever and clutch for this purpose. It will be understood that the clutch may be of any 90 suitable form and so connected to the lever that it is engaged when the lever is lowered. The lowering of the lever engages the clutch but the rising of the clutch control automatically releases the lever. 95

The controlling mechanism carried by the lever may be broadly described as counting mechanism under the influence of which the clutch is disengaged when the press has functioned the predetermined number of 105 times, secondly means for setting the mechanism so that the clutch is disengaged after each operation of the press, and thirdly means whereby the clutch control may be held inoperative by the operator so that the 110

press may function for an unlimited number of times and in fact until the operator releases this particular control.

As previously stated, a spring is provided 5 normally seeking to release the clutch and a plunger 4 is mounted along the lever the extremity of which engages with a notch 5 on a clutch controlling member 6 connected to the rod 3 and serves to hold the clutch 10 engaged, this plunger automatically engaging with the clutch control on the downward movement of the lever after it has been raised, the lowering of the lever thus bringing down the clutch control.

15 The lever is provided with a pin 65 and the clutch control with a slot 66 so as to permit the lever to be raised without a full corresponding movement of the clutch release, but this pin and slot merely serve to 20 retain the part 6 in its requisite relation to the lever and does not provide an actuating connection. The plunger is advanced by a spring 67, but when the plunger is retracted 25 the clutch control rises automatically. It will, however, be understood that the clutch control rises to a limited extent before the lever is released.

The ram or other movable part of the press carries or actuates a sliding member 7 30 having an incline 8 which may engage with the plunger 4 at each operation of the press so as to withdraw it from the clutch release, or may not withdraw it according to the setting of the other mechanism as hereinafter 35 explained. This inclined member 7 slides up and down in a slot 9 in the plunger 4 and when it is required that the plunger shall be moved means are provided in the form of a block 10 free to slide along the 40 lever which block engages with the opposite or back edge of the vertically sliding member so that when the inclined part 8 engages the plunger 4 the plunger is withdrawn, but when the sliding block 10 is away from the 45 vertically sliding member 7 the vertically sliding member is merely moved backwardly (i. e., away toward the lever pivot) when the incline engages the plunger, without moving it.

50 The means for bringing the sliding block 10 into position against the vertically sliding member 7 so as to cause the clutch mechanism to operate at each movement of the press preferably takes the form of a handle 55 11 pivoted upon the end of the lever at 12 and provided with a trigger 13 engaging with a slide 14 which is connected to a reciprocating member 15 behind the sliding block by means of the member 16, so that 60 when the handle is in its normal position the sliding block is held against the vertically moving inclined member 7 causing the plunger 4 to move at each operation of the press. The member 15 is adapted to move in a direction at right angles to the length of the

lever and also in a direction corresponding with the length of the lever. The trigger provides merely a safety device for normally retaining the pivoted handle in position so that the plunger is operated at each movement of the press. The connection between the pivoted handle 11 and the sliding or connecting member 14 is such that when the pivoted handle is lowered or moved angularly relatively to the lever as to the position shown in Fig. 4, the supporting member 15 behind the sliding block 10 is retracted so that the clutch remains continually engaged. The handle 11 is pivoted upon the end of the lever 1 at 12 while its lower end has an inclined slot 18 which engages a pin 19 in an extension 20 of the slide 14 so that depression of the handle will cause the slide to move away from the handle and toward the pivoted end of the lever. The pin 12 is shown as operating in a horizontal slot which is in the part 20 this pin permitting movement of said part 20 relatively to the lever and handle.

The supporting member 15 is in the form 90 of a vertically moving slide having an inclined portion 24 or projection which lies immediately behind the sliding block 10, the vertically sliding member being, as previously stated, retracted by the handle. In 95 addition to a movement in a direction corresponding with the length of the lever, the supporting member is movable at right angles to the length of the lever under the influence of a foot control 25, 26 so that 100 when the foot control is depressed the incline 24 is drawn down from behind the sliding block, when the sliding block will then be retracted each time the machine functions instead of causing the plunger to 105 move. By this means the machine may function for an unlimited number of times even when the handle is in its raised position so long as the operator's foot is on the control, but this mechanism may be rendered inoperative by inserting a screw or abutment in the part 27^a beneath the end 28 of the part 15. The member 15 is normally held up by the spring 27, which acts on the top of the guide block 27^a which is fixed to 110 the lever and serves as a guide for the plunger 4.

The means for causing the plunger to be released and the machine stopped only at the end of a predetermined number of movements greater than one movement, may take the form of a ratchet wheel 31 mounted upon the main body of the machine and which moves one tooth for each movement of the press, the ratchet wheel being provided 120 with a movable stop 32, which can be secured in any one of the holes 33 so that at the end of the predetermined number of movements the sliding block 10 which has previously been freed by lowering the control- 125 130

ling handle 11 will be advanced so as to cause the plunger to be operated.

Carried by the spindle of the ratchet wheel is a lever 34 which is engaged by an abutment 5 or collar 35 upon the aforementioned vertically reciprocating inclined member 7 so that each time the inclined member rises this lever 34 is lifted. This lever carries a spring controlled pawl 36 engaging with the 10 ratchet wheel so that each time the lever rises the ratchet wheel moves one tooth, a second pawl 37 being provided which retains the wheel in its adjusted position when the first pawl moves down again. As stated, 15 an adjustable stop 32 is provided which may take the form of a block screwed upon the side of the wheel which is set in the desired position upon the wheel, so that after the desired number of movements of the 20 press have been made the stop will engage with a bell crank lever 38 carried by a part 38^a secured to the lever 1, the bell crank lever being connected to the sliding block 10 by a link 39 so as to press such block against 25 the rear of the aforementioned vertically reciprocating member 7, the connection between the block 10 and link 39 being through the medium of a pin 40 and slot 41 so as to permit the sliding block to recede when the 30 bell crank lever is in its normal lowered position. By lowering or removing the part 35 the counting mechanism may be rendered inoperative and the machine caused to function once only, or as long as permitted by 35 the pedal 26.

Means are provided for automatically restoring the counting mechanism to zero when the machine is stopped such means including mechanism as pegs 43, 44 carried 40 by the clutch releasing member 6, so that whenever such clutch release is lowered to start the machine the pegs 43, 44 engage with the two pawls and lift them clear of the ratchet wheel which is then rotated backwardly under the influence of a chain 45 and weight 46 or spring, diagrammatically indicated at Figs. 2 and 3.

Thus the machine will function for a predetermined number of times according to 50 the setting of the stop upon the ratchet wheel enabling the desired number of pressing operations to be performed as may be required to complete the working of one strip of metal without requiring the machine to be stopped between each operation.

Means are provided for preventing the raising of the lever 1 while the clutch is engaged such means comprising a locking catch 55 pivotally mounted on a bracket 60 fixed to the frame of the press adapted to engage with the upper edge of the lever when the lever is lowered and holds the lever in its lowered position. The locking catch 55 is provided with a weighted arm to normally hold it in engagement with the lever.

The clutch control 6 has an incline 57 which engages a peg 58 on locking the catch 55 when the clutch control rises and thus retracts the locking catch from engagement with the lever allowing the same to rise and 70 retains the locking catch disengaged until the clutch control is again brought down.

Although we have spoken of the raising and lowering of the lever it will be understood that the lever may be arranged at any 75 desired angle.

As shown the plunger 4 passes through the sliding block 10 and reciprocating member 15 but each of these members is cut away so as to permit them to freely move at right 80 angles to the said plunger while the plunger is cut away to permit the member 7 to pass through it. The connection between the members 15 and 16 is through the medium of a pin and slot 69 which permits the member 85 15 to rise and fall independently of the part 16.

To prevent the machine operating except when the lever is down the ram of the press may be provided with an adjustable 90 screw abutment 70 adapted to be engaged by a horizontal plunger 71 controlled by an inclined slot 72 in vertical slide 73 connected to the lever by a link 74, as shown by dotted lines in Fig. 1 and so arranged 95 that when the lever is lowered the plunger is disengaged, and engaged when the lever is raised.

What we claim then is:—

1. Controlling mechanism for power 100 presses and other purposes embodying in combination a lever; a clutch control; a locking device carried by said lever and adapted to engage said clutch control and hold it in its inoperative position; a locking device 105 control actuated by a moving part of the machine; and means for causing said locking device control to release the locking device and clutch control at the end of a predetermined but variable number of machine 110 operations.

2. Controlling mechanism for power 115 presses and other purposes embodying in combination a lever; a clutch control; a plunger carried by said lever and adapted to engage said clutch control and hold it in its inoperative position; a plunger control actuated by a moving part of the machine; and means for causing said plunger control to retract the plunger and release the clutch 120 control at the end of a predetermined but variable number of machine operations.

3. Controlling mechanism for power 125 presses and other purposes embodying in combination a lever; a clutch control; a plunger carried by said lever; a plunger control connected to and reciprocated by a moving part of the machine, said plunger control having an incline adapted to retract the plunger and thus release the clutch control; a slid- 130

- ing block behind the plunger control; a handle pivoted to said lever and connected to said sliding block so that when the handle is operated the sliding block is retracted whereupon the plunger is not retracted by the plunger control; and means for advancing the sliding block when the machine has functioned a predetermined number of times.
- 10 4. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted whereupon the plunger is not retracted by the plunger control; a ratchet wheel; a rocking lever adapted to be operated by the plunger control; a pawl carried by said rocking lever and whereby the ratchet wheel is rotated one tooth each time the plunger control moves; an abutment on the ratchet wheel; and a lever connected to said sliding block and adapted to advance same when struck by the abutment.
5. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted whereupon the plunger is not retracted by the plunger control; a ratchet wheel; a rocking lever adapted to be operated by the plunger control; a pawl carried by said rocking lever and whereby the ratchet wheel is rotated one tooth each time the plunger control moves; an abutment on the ratchet wheel; a lever connected to said sliding block and adapted to advance same when struck by the abutment, and means for automatically restoring the ratchet wheel to zero when the main lever is raised.
6. Controlling mechanism for power presses embodying in combination a lever; a clutch control; a locking device carried by said lever and adapted to engage said clutch control and hold it in its inoperative position; a locking device control actuated by a moving part of the machine; means for causing said locking device control to release the locking device and clutch control at the end of a predetermined but variable number of machine operations; and a press guard carried by said lever.
7. Controlling mechanism for power presses and other purposes embodying in combination a lever; a clutch control; a locking device carried by said lever and adapted to engage said clutch control and hold it in its inoperative position; a locking device control actuated by a moving part of the machine; means for causing said locking device control to release the locking device and clutch control at the end of a predetermined number of machine operations; and means adapted to be controlled by the machine operator for causing the machine to operate irrespective of the number of operations for which the machine has been set.
8. Controlling mechanism for power presses and other purposes embodying in combination a lever; a clutch control; a plunger carried by said lever and adapted to engage said clutch control and hold it in its inoperative position; a plunger control actuated by a moving part of the machine; means for causing said plunger control to retract the plunger and release the clutch control at the end of a predetermined number of machine operations; and means adapted to be controlled by the machine operator for causing the machine to operate irrespective of the number of operations for which the machine has been set.
9. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted whereupon the plunger is not retracted by the plunger control; means for advancing the sliding block when the machine has functioned a predetermined number of times; and means adapted to be controlled by the machine operator for causing the machine to operate irrespective of the number of operations for which the machine has been set.
10. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted where-

- upon the plunger is not retracted by the plunger control; a ratchet wheel; a rocking lever adapted to be operated by the plunger control; a pawl carried by said rocking lever and whereby the ratchet wheel is rotated one tooth each time the plunger control moves; an abutment on the ratchet wheel; a lever connected to said sliding block and adapted to advance same when struck by the abutment; and means adapted to be controlled by the machine operator for causing the machine to operate irrespective of the number of operations for which the machine has been set.
11. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted whereupon the plunger is not retracted by the plunger control; means for advancing the sliding block when the machine has functioned a predetermined number of times, and means for retaining the handle in its adjusted position.
12. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted whereupon the plunger is not retracted by the plunger control; a ratchet wheel; a rocking lever adapted to be operated by the plunger control; a pawl carried by said rocking lever and whereby the ratchet wheel is rotated one tooth each time the plunger control moves; an abutment on the ratchet wheel; a lever connected to said sliding block and adapted to advance same when struck by the abutment; and means for retaining the handle in its adjusted position.
13. Controlling mechanism for power presses and other purposes embodying in combination a lever; a clutch control; a locking device carried by said lever and adapted to engage said clutch control and hold it in its inoperative position; a locking device control actuated by a moving part of the machine; means for causing said locking device control to release the locking device and clutch control at the end of a predetermined number of machine operations; means for locking the lever in its operative position; and means for releasing said lever back when the clutch control is released.
14. Controlling mechanism for power presses and other purposes embodying in combination a lever; a clutch control; a plunger carried by said lever and adapted to engage said clutch control and hold it in its inoperative position; a plunger control actuated by a moving part of the machine; means for causing said plunger control to retract the plunger and release the clutch control at the end of a predetermined number of machine operations; means for locking the lever in its operative position; and means for releasing said lever back when the clutch control is released.
15. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted whereupon the plunger is not retracted by the plunger control; means for advancing the sliding block when the machine has functioned a predetermined number of times; means for locking the lever in its operative position; and means for releasing said lever back when the clutch control is released.
16. Controlling mechanism for power presses and other purposes embodying in combination a lever; a clutch control; a plunger carried by said lever; a plunger control connected to and reciprocated by a moving part of the machine, said plunger control having an incline adapted to retract the plunger and thus release the clutch control; a sliding block behind the plunger control; a handle pivoted to said lever and connected to said sliding block so that when the handle is operated the sliding block is retracted whereupon the plunger is not retracted by the plunger control; a ratchet wheel; a rocking lever adapted to be operated by the plunger control; a pawl carried by said rocking lever and whereby the ratchet wheel is rotated one tooth each time the plunger control moves; an abutment on the ratchet wheel; a lever connected to said sliding block and adapted to advance same when struck by the abutment; and means for locking the lever in its operative position; and means for releasing said lever back when the clutch control is released.

17. Controlling mechanism for power presses and other purposes embodying in combination, a clutch control, a hand operated pivoted starting lever, means for connecting said lever and clutch control so that the latter is operated when the lever has almost reached the end of its travel, means for locking the lever in its operative position, and means for automatically releasing the lever after each operation.

18. Controlling mechanism for power presses and other purposes embodying in combination, a clutch control, a hand operated pivoted starting lever connected to said clutch control through the medium of a pin and slot, means for locking the lever in its operative position, and means for automatically releasing the lever after each operation.

19. Controlling mechanism for power presses and other purposes embodying in combination, a clutch control, a pivoted starting lever, a spring advanced plunger carried by the lever and adapted to engage with said clutch control, a reciprocating member actuated by a movable part of the press adapted to engage with said plunger, a block slideable along said lever, a pivoted handle on said lever, and means connecting said handle and sliding block so that when the handle is in one position the block is adjacent the reciprocating member and will thus cause the press to automatically stop after each operation while, when the handle is in another position, the block is retracted and the press will function for an indefinite number of times.

20. Controlling mechanism for power presses and other purposes embodying in combination, a clutch control, a pivoted starting lever, a spring advanced plunger carried by the lever and adapted to engage with said clutch control, a reciprocating member actuated by a movable part of the press adapted to engage with said plunger, a block slideable along said lever, a pivoted handle on said lever, means connecting said handle and sliding block so that when the handle is in one position the block is adjacent the reciprocating member and will thus cause the press to automatically stop after

each operation, while, when the handle is in another position, the block is retracted and the press will function for an indefinite number of times, and means for locking the handle in each of its two positions.

55

21. Controlling mechanism for power presses and other purposes, embodying in combination, a clutch control, a pivoted starting lever, a spring advanced plunger carried by the lever and adapted to engage with said clutch control, a reciprocating member actuated by a movable part of the press adapted to engage with said plunger, a block slideable along said lever, a spring raised member immediately behind the sliding block, and a pedal connected to said spring raised member and adapted normally to cause the machine to stop after each operation, but when depressed to allow the machine to function for an indefinite number of operations.

60

22. Controlling mechanism for power presses and other purposes embodying in combination, a clutch control, a pivoted starting lever, a spring advanced plunger carried by the lever and adapted to engage with said clutch control, a reciprocating member actuated by a movable part of the press adapted to engage with said plunger, a block slideable along said lever, a pivoted handle on said lever, means connecting said handle and sliding block so that when the handle is in one position the block is adjacent the reciprocating member and will thus cause the press to automatically stop after each operation, while, when the handle is in another position, the block is retracted and the press will function for an unlimited number of times, a spring raised member immediately behind the sliding block, and a pedal connected to said spring raised member and adapted to normally cause the machine to stop after each operation, but when depressed to allow the machine to function for an indefinite number of operations.
